(57) **CLAIM**

The ornamental design for an engine hood for a vehicle, as shown and described.

DESCRIPTION

FIG. 1 is a perspective view of an engine hood for a vehicle, taken from the front.

FIG. 2 is a front view of the engine hood for a vehicle of FIG. 1.

FIG. 3 is a right-side view of the engine hood for a vehicle of FIG. 1.

FIG. 4 is a back view of the engine hood for a vehicle of FIG. 1.

FIG. 5 is a left-side view of the engine hood for a vehicle of FIG. 1.

FIG. 6 is a top view of the engine hood for a vehicle of FIG. 1; and,

FIG. 7 is a bottom view of the engine hood for a vehicle of FIG. 1.

The grey tones are gradient shading, to illustrate contour, and form no part of the claimed design.
